UNITED STATES PATENT OFFICE

FRANK BURTON SHEPARD, OF TEXON, TEXAS

LEAD CLAMP

Application filed February 11, 1928. Serial No. 253,711.

This invention relates to lead clamps and more particularly to clamps for use in hot line work.

An important object of the invention is to produce a device of this character which may be readily applied to a line without the necessity of cutting off current therein and without danger to the workman.

A further object of the invention is to produce a clamp which may be very readily and cheaply constructed and which, at the same time, will provide an efficient and permanent connection between the line and the lead therefrom.

15 A further object of the invention is to provide a clamp which may be readily manipulated with the hot sticks usually employed in high tension work.

20 A still further object is to provide a device which will provide an electrical bond between aluminum and copper wires which will be permanent in its nature.

25 These and other objects I attain by the construction shown in the accompanying drawings, wherein for the purpose of illustration is shown a preferred embodiment of my invention and wherein:—

Figure 1 is a side elevation showing a lead clamp constructed in accordance with my invention and illustrating the method of applying the clamp to a line wire;

Figure 2 is a front elevation thereof;

Figure 3 is a section on the line 3—3 of Figure 1;

35 Figure 4 is a section on the line 4—4 of Figure 2;

Figure 5 is a transverse sectional view through a modified type of clamp;

Figure 6 is a side elevation thereof.

40 Referring now more particularly to the drawings, the clamp is formed in two sections, one of which designated at 10 may be termed the body of the clamp. This body is formed at one end thereof with a hooked terminal portion 11, the face of the body ad-

jacent the hook being provided with a transverse groove 12. At a point spaced from the groove 12 longitudinally of the body, a second transverse groove, the bottom of which is arcuately curved, is provided, as indicated at 13. Through the body intermediate these grooves an opening 14 is formed for the passage of a bolt, generally designated at 15. The second section of the clamp, which might be termed the jaw 16, has formed therein at one end thereof a transversely extending groove 17 having an arcuately curved bottom. At its opposite end, the jaw is formed at the same face with an outstanding flange 18, the end face of which is convexly curved to fit against the concave bottom of the groove 13. The bolt 15 above referred to has a head 19, the inner face of which is arcuately curved, as indicated at 20.

Beneath the head, a squared portion 21 is formed upon the shank of the bolt. The remainder of the shank is circular in cross section and is provided with a relatively long threaded portion 22. The outer face of the head is formed with an eye 23. The outer face of the jaw 16 has formed therein a concave socket for the reception of the inner face of the bolt, as indicated at 24, and through the body is formed a rectangular opening 25 for the passage of the squared portion 21 of the shank. It will be obvious that this jaw must remain in a position fixed by the bolt.

In assembling the clamp, the bolt is passed through the sections thereof and the nut applied against the outer face of the body 10, the nut being left sufficiently loose, so that the space between the body and jaw is sufficient to admit the line wire. A hot stick is employed having in its end a prong 26 to extend through the opening of the eye 23 and from this stick, the clamp is supported. A second hot stick is provided having rotatably mounted upon the upper end thereof one end of a wrench 27, the opposite end of which

has a socket for the reception of the nut. After the wire line has been engaged, the second hot stick is operated as a connecting rod to cause rotation of the wrench 27, thereby tightening the jaw 16 upon the line wire. At this time, the jaw moves about the end of the flange 13 as a pivot, such movement being permitted by providing sufficient space in the opening 25 to permit oscillation of the clamp with relation thereto. The rounded inner face of the head coacting with the curved seat 24 maintains a firm contact between the bolt and jaw in all positions thereof.

In order to provide for attachment of the lead 28 to the body 10, this body is elongated and is provided with a cast-in metallic insert 29. As is well known to those familiar with the art, the line wires now commonly employed are usually of aluminum or aluminum composition and copper connections cannot be permanently made therewith by bolting. I, therefore, cast-in the insert 29, as above described, and make this insert of copper, so that the copper lead terminal 30 may be held thereagainst by a bolt 31, which preferably passes entirely through the body, the insert and the terminal. In some instances, it is necessary to connect parallel wires of different materials such as aluminum and copper. Under these circumstances, I employ a clamp such as shown in Figure 5. This clamp consists of two similar body sections 33 and 34, each having parallel longitudinally extending grooves 35 and 36. The bottoms of these grooves are concavely curved and in each instance, the wall of the groove 36 is faced with a copper insert 37 cast integrally with the body. Bolts similar to the bolt 15 are employed for clamping these sections together upon the wires to be connected.

It will be obvious that by employing a construction of this character, not only is a convenient means provided for making connections to hot lines but likewise a means is provided, whereby an aluminum copper connection may be made with the assurance of a permanent joint.

Since the construction hereinbefore set forth is capable of a certain range of change and modification without materially departing from the spirit of the invention, I do not limit myself to such specific structure except as hereinafter claimed.

I claim:—

A lead clamp comprising a body having a transverse groove, a jaw having a flange abutting the body in spaced relation to the groove, said jaw having a groove opposing the groove of the body, and a securing element passing through the jaw and body at a point intermediate the groove and flange of the jaw, said securing element having a head formed with an eye for the passage of the pin of a handle, the inner surface of the head being

rounded, the opposed portion of the jaw having a concave socket, the securing element at the point of its passage through the jaw being squared and loosely fitting in a correspondingly shaped opening in the jaw, said squared portion being adapted to prevent rotation of said jaw about said securing member.

In testimony whereof, I hereunto affix my signature.

FRANK BURTON SHEPARD.
